(57) **CLAIM**

The ornamental design for a smart cat litter box, as shown and described.

DESCRIPTION

FIG. 1 is a front, right and top perspective view of a smart cat litter box showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 in FIG. 1;

FIG. 10 is an enlarged view of area 10 in FIG. 1; and,

FIG. 11 is an enlarged view of area 11 in FIG. 2.

The broken lines in the figures illustrate portions of the smart cat litter box that form no part of the claimed design. The dot-dash broken lines represent boundaries of the enlarged portions and form no part of the claimed design.
